UNITED STATES PATENT OFFICE

BARNEY A. KEHOE, OF CEDAR RAPIDS, IOWA

DESIGN FOR A COMBINATION LAMP BASE AND SIGN

Application filed May 7, 1930. Serial No. 35,520. Term of patent 7 years.

To all whom it may concern:

Be it known that I, BARNEY A. KEHOE, a citizen of the United States, residing at Cedar Rapids, in the county of Linn and State of Iowa, have invented a new, original, and ornamental Design for Combination Lamp, Base and Sign, of which the following is a specification, reference being had to the accompanying drawings, forming part thereof, wherein—

Fig. 1 is a front elevation of my design.
Fig. 2 is a side elevation of the same; and
Fig. 3 is a top plan view of the same.

What I claim is:

The ornamental design for combination lamp base and sign substantially as shown.

BARNEY A. KEHOE.
